UNITED STATES PATENT OFFICE.

JOHN F. W. KROEGER, OF BOGOTA, NEW JERSEY, ASSIGNOR TO ROGERS & THOMPSON, INC., OF NEW YORK, N. Y., A CORPORATION OF NEW YORK.

COLOR-CARD.

1,175,960.

Specification of Letters Patent. Patented Mar. 21, 1916.

Application filed June 22, 1915. Serial No. 35,546.

To all whom it may concern:

Be it known that I, JOHN F. W. KROEGER, a citizen of the United States, and a resident of Bogota, in the county of Bergen and State of New Jersey, have invented 5 certain new and useful Improvements in Color - Cards, of which the following is a specification.

This invention relates to color cards generally used by persons dealing in textile fabrics and the like, wherein a plurality of sections of textile fabrics of varying colors and styles are secured to the card so that the purchaser can select from the card the 10 color and style of textile fabric desired.

The style of color card generally in use at the present time consists of an ordinary card, upon the surface of which have been adhesively secured small sections of the 15 fabric. In some instances the card is merely colored to represent the colors of the various kinds of textile fabric. This method is very inconvenient to the purchaser as the 20 desired color and style of fabric desired cannot be quickly and easily located.

The object, therefore, of this invention is to provide a color card of such construction so that the desired color and style of merchandise desired can be located with a minimum of trouble. The color card provided 25 by me is also ornamental in appearance and may be used for the purposes, as will be described hereinafter.

My invention is capable of being embodied in various ways and it resides in the 30 construction and combination of parts hereinafter described and falling within the scope of the claims appended hereto.

For a more particular description of my 35 invention, reference is to be had to the accompanying drawings, in which—

Figure 1 is a face view of my improved color card; Fig. 2 is an edge view of a portion of the same; Fig. 3 is a view of the 40 color card in a closed position; Fig. 4 is a sectional view on the line 4—4 of Fig. 1, looking in the direction of the arrows; and Fig. 5 is a view of a portion of the face of the color card, part of the same being 45 broken away.

Throughout the various views of the drawing, similar reference characters designate similar parts.

I have shown a color card consisting of 50 a foldable fan, but it is obvious that the

same may be embodied in a strip of any foldable, flexible material.

The fan is made up in a generally conventional manner and has two end strips 1, of wood, metal, bone or other desired material 60 and a series of intermediate ribs 2, the end strips and intermediate ribs being pivoted at the inner end, or portion of the fan 65 grasped by the hand, on a pin 3.

Stretched from one of the end strips to 65 the other end strip is the fan covering 4, comprising a face portion 5 and backing portion 6, the covering being arranged with a series of folds 7, allowing a folding of the fan in the conventional manner, the outer 70 ends of the ribs 2 being interposed and secured between the face portion 5 and backing portion 6.

A series of openings 8 are formed in the face portion of the fan covering on the lines 75 of the folds 7. A plurality of sections of textile material 9 of varying colors and styles of material are adhesively secured adjacent their edges between the face portion 5 and backing portion 6, the center 80 portions of said sections 9 projecting loosely through the openings 8 in the face portion.

Secured to one of the end strips 1 is a 85 flexible cover 10 for the fan, said cover arranged to fold on the dotted lines 11 about the fan and retain the same in a closed position. On the strip 1 is arranged a portion of a snap fastener 12 or other securing device and on the outer end of the cover 10 90 is a strip of solid material such as wood, metal, etc., and on the same is arranged a portion of a snap fastener 13 coöperating with the portion 12 to keep the cover in 95 position when the same is wrapped about the fan.

From the foregoing, my improved color card will be readily understood.

When the fan is closed as shown in Fig. 3, the colors are bunched together so that 100 the desired color can readily be selected and the fan opened to that color. As above mentioned, however, my improved color card need not be made in the form of a fan, 105 as it is made that way for convenience and usefulness, but can be made in any other form wherein a strip of flexible and folded material is incorporated.

Having described my invention, it is obvious that the same is not limited to the 110

embodiment herein shown, but is broad enough to cover all structures coming within the scope of the annexed claims.

What I claim is:

- 5 1. A color card or the like comprising a foldable fan, a series of openings arranged in said fan and along the lines of its folds, and sections of textile material secured in said openings and overlying the fold, to be displayed when the card or fan is folded.
- 10 2. A color card or the like comprising a

foldable fan having a series of openings arranged on its face portion along the lines of its folds, a backing portion secured to the face portion and a plurality of pieces 15 of textile material secured between the face portion and backing portion and projecting through the openings in the face portion.

Signed at the city of New York, county of New York, and State of New York, this 20 10th day of June, 1915.

JOHN F. W. KROEGER.
